[57] CLAIM

The ornamental design for a limb holder, as shown.

DESCRIPTION

FIG. 1 is a top view of the present limb holder illustrating the opposed straps in a folded position; FIG. 2 is a bottom plan view of the limb holder shown in FIG. 1;

FIG. 3 is a side view of the limb holder as shown in FIG. 1; and

FIG. 4 is an enlarged sectional view taken generally along sectional lines 4—4 in FIG. 2.
